UNITED STATES PATENT OFFICE

EUGENE L. BARNES, OF BUFFALO, NEW YORK

REFRIGERATING APPARATUS

Application filed February 15, 1928. Serial No. 254,336.

My invention relates to an improvement in refrigerating apparatus and more particularly to means for effecting the removal of lubricant from the refrigerant chamber of such apparatus.

In refrigerating apparatus, of the character to which my invention more particularly relates and which comprises generally speaking a compressor for the refrigerant and a boiler or evaporator in association with a chamber into which the compressed refrigerant is delivered by the compressor, it has been found that lubricant necessary to the operation of the compressor is delivered by the compressor into the refrigerant chamber and since the lubricant will not evaporate, as does the refrigerant, such lubricant as is delivered to the refrigerant chamber is lost to the compressor and accumulates undesirably in the refrigerant chamber and boiler.

The tendency of lubricant to accumulate in the refrigerant chamber of refrigerating apparatus has militated against the use of petroleum oil as a lubricant, especially where ethyl chloride, which forms a desirable and efficient refrigerant, is used, since petroleum oil and ethyl chloride will form a solution and, since ethyl chloride is being continuously evaporated in the refrigerant chamber an undesirable concentration of lubricant will result.

Now, in accordance with my invention I provide means for removing lubricant from the refrigerant chamber of refrigerating apparatus of a simple and inexpensive character and which will operate to prevent accumulation of lubricant in the chamber and maintain the concentration thereof in the refrigerant at a minimum and at the same time enable the return of lubricant removed from the refrigerant chamber to the compressor.

Having now indicated in a general way the nature and purpose of my invention, I will proceed to a detailed description of a pre-

ferred embodiment thereof with reference to the accompanying drawings in which:—

Figure 1 is a view, partly broken away, of a refrigerant chamber and boiler embodying my invention.

Figure 2 is a rear view, partly in section, of the subject of Figure 1.

Figure 3 is a view showing a detail of construction.

In the drawings *a* indicates a refrigerant chamber, of any usual construction, provided with a supply conduit *b*, one end of which communicates with a conduit *c* through which liquid refrigerant is supplied by a compressor (not shown) and the other end of which is provided with an outlet opening controlled by a valve indicated at *d*, the operation of which is effected through the medium of a float *e* to which it is connected by means of a lever *f*, the arrangement being such that liquid refrigerant will be maintained in the chamber substantially at a level indicated by the broken line *g*.

Within the chamber *a* is positioned a sump *h*, the lower end of which is below the normal level of the liquid refrigerant and the upper end of which is open and above the normal level of the liquid refrigerant. An exhaust conduit *i*, for vaporized refrigerant which collects in the chamber above the liquid refrigerant, extends into the sump to a point near the bottom thereof and is connected to a conduit *j*, through which vaporized refrigerant is withdrawn under the influence of the compressor.

Supported by the sump *h* is a U-shaped tube *k*, one leg of which extends into the sump to a point adjacent the end of tube *i* and the other leg of which extends outside of the sump into the liquid refrigerant. The tube is so arranged that its ends are at the same level. The tube *k* is of relatively small internal diameter and is loaded with a wick, for example, of wool, as shown at *x*, Figure 1, or formed from a number of very small

wires, as shown at *y*, Figure 3. For example, the tube may be of standard $1\frac{1}{8}$ " O. D. copper tubing loaded with a wick of wool or one formed by, for example, thirty-four wires of .0010" diameter.

5 The refrigerant chamber *a* is, as is usual, associated with a boiler or evaporator comprising upper and lower headers *m* connected in pairs by a plurality of vertically extending tubes *n*. The upper headers are connected to the upper part of the chamber *a* by conduits *o*, to enable the return of vaporized refrigerant to the chamber, and the lower headers are connected to the lower part of the 10 chamber *a* by means of conduits *p* to enable the supply of liquid refrigerant to the boiler from the chamber. Between the sets of vertical tubes *n* a casing *c* having a door *r* is provided for the reception of the usual ice trays *s*. 15

20 In the operation of the apparatus liquid refrigerant is supplied to the chamber *a* by a compressor and fills the headers *m* and tubes *n* to a level determined by the float *e*. The liquid refrigerant in extracting heat 25 from the atmosphere surrounding the boiler vaporizes and the vapor passes from the upper headers *m* to the upper portion of chamber *a*. Vaporization of the refrigerant results in a lowering of the level of liquid refrigerant in chamber *a* and as the float *e* drops, the valve *d* is opened and further liquid refrigerant is supplied to the chamber, while at the same time vaporized refrigerant 30 is withdrawn from the chamber through 35 sump *h* and conduit *i*.

During the operation of the compressor, as when liquid refrigerant is supplied to chamber *a* and vaporized refrigerant is withdrawn therefrom, the wick in tube *k* acts by capillary 40 action to transfer liquid refrigerant drop by drop from the chamber to the sump from which it is withdrawn by the compressor through conduit *i*. The capillary action of the wick in tube *k* will continue during operation 45 of the compressor and after the compressor is stopped until the level of liquid refrigerant in the sump reaches that of the liquid refrigerant in the chamber. When the compressor is restarted after a period of inactivity 50 the relatively small amount of liquid refrigerant which may have collected in the sump will be drawn out through conduit *i* and will flash into gas before reaching the compressor, as will the liquid refrigerant entering 55 the sump through tube *k* during the continued operation of the compressor.

The liquid refrigerant transferred from the chamber *a* into the sump and withdrawn therefrom by the compressor will contain lubricant contained in the liquid refrigerant, which lubricant will be withdrawn from the sump with the liquid refrigerant, then separated therefrom on its flashing into gas and finally will be returned to the compressor.

65 Through the transfer of liquid refrigerant

from the chamber *a* to the sump through tube *k* there will be a complete change of liquid refrigerant in the chamber *a* and boiler periodically and the apparatus may be desirably so designed and proportioned that a complete change of refrigerant will be effected about every forty-eight hours, though it will be understood that the apparatus may be readily designed so that the change will be effected in any other desired period of time. 75

It will now be noted that through the withdrawal of liquid refrigerant and lubricant from the chamber *a* accumulation of lubricant in the chamber and boiler is avoided and lubricant which would be lost to the compressor is returned thereto. 80

It will be understood that my invention may be adapted to other forms of refrigerating apparatus than that described herein.

Having now fully described my invention, 85 what I claim and desire to protect by Letters Patent is:—

1. In a refrigerating apparatus, in combination, a refrigerant chamber, means for maintaining liquid refrigerant in said chamber, a sump within said chamber extending below the level of liquid refrigerant therein, a vapor discharge conduit extending into said sump and means extending beneath the level of refrigerant in said chamber and into said sump whereby liquid refrigerant is transferred from said chamber into said sump by capillary action. 90

2. In a refrigerating apparatus, in combination, a refrigerant chamber, means for maintaining liquid refrigerant in said chamber, a sump within said chamber extending below the level of liquid refrigerant therein, a vapor discharge conduit extending into said sump, a tube, one end of which is positioned within said sump and the other end of which is positioned below the level of refrigerant in said chamber and a wick within said tube. 100

3. In a refrigerating apparatus, in combination, a refrigerant chamber, means for maintaining liquid refrigerant in said chamber, a sump within said chamber extending below the level of liquid refrigerant therein, a vapor discharge conduit extending into said sump, a tube, one end of which is positioned within said sump and the other end of which is positioned below the level of refrigerant in said chamber, said tube being arranged with its ends at the same level, and a wick within said tube. 110

4. In a refrigerating apparatus, in combination, a refrigerant chamber, means for maintaining liquid refrigerant in said chamber, a sump within said chamber extending below the level of liquid refrigerant therein, a vapor discharge conduit extending into said sump, a U tube positioned to extend within said sump and beneath the level of 120

125

refrigerant in said chamber and a wick within said tube.

5. In a refrigerating apparatus, in combination, a refrigerant chamber, means for maintaining liquid refrigerant in said chamber, a sump within said chamber extending below the level of liquid refrigerant therein, a vapor discharge conduit extending into said sump, a U tube positioned to extend 10 within said sump and beneath the level of refrigerant in said chamber and a wick formed by a plurality of fine wires within said tube.

In testimony of which invention, I have 15 hereunto set my hand, at Buffalo, New York, on this seventh day of February, 1928.

EUGENE L. BARNES.
